UNITED STATES PATENT OFFICE.

JUDSON L. HAND, JR., OF PELHAM, GEORGIA.

FURNACE CONSTRUCTION.

1,198,841.

Specification of Letters Patent. Patented Sept. 19, 1916.

Application filed March 20, 1914. Serial No. 826,062.

To all whom it may concern:

Be it known that I, JUDSON L. HAND, Jr., a citizen of the United States, residing at Pelham, in the county of Mitchell and State 5 of Georgia, have invented certain new and useful Improvements in Furnace Construction, of which the following is a specification.

The object of the invention is to provide 10 for the relative protection of the rear-end construction of furnaces, more especially of the continuous or moving grate type, and to provide means of protection of such a character as to conserve and utilize to the maximum extent the heat generated, and to economize in the consumption of fuel, while 15 minimizing deterioration due to excessive local heating of particular elements, and facilitating the replacement or substitution of 20 burned out elements.

With these objects in view, the invention consists in the provision of means for inducing the circulation of a cooling agent, consisting of a combustion-supporting medium, 25 adjacent to the exposed surfaces of those elements of the furnace construction which are subjected to the heat and which are least protected by the refuse consisting of ash, etc., and minimizing the exposure of said 30 parts to the direct radiant heat from the fire bed, and in utilizing the heat extracted from said furnace elements by returning it to the fire bed under such conditions as will increase the supply of combustion-supporting 35 medium; and while a preferred embodiment of the construction is illustrated in the accompanying drawing, it will be understood that various changes in the form, proportions and minor details of the construction 40 may be resorted to without departing from the spirit of the invention.

In the drawings,—Figure 1 is a general diagrammatic view in longitudinal section of a boiler furnace embodying the invention; Fig. 2 is a detail sectional view of the inner or rear end portion of the furnace, showing means for conducting the cooling agent, and the relation between the rear end furnace elements and the bridge wall; Fig. 45 3 is a plan view partly in section of the dump plate and related parts, showing the means for conveying the cooling agent; Fig. 4 is a sectional view on the line 4—4 of Fig. 3; Fig. 5 is a detail sectional view on

the line 5—5 of Fig. 2, to show the sectional 55 construction of the apron members.

As is usual in constructions of this character, the parts are arranged in such a way as to prevent the influx of air at the rear end of the furnace, with the object of minimizing 60 the heat at that portion of the furnace, and to that end the girders 10 are disposed at such interval at their lower portions as to provide for a substantially complete closure therebetween, when the dump plate 11 is in 65 its normal position, as illustrated in Fig. 2, said girders supporting the aprons 12 which are arched to hold back the unconsumed fuel, while permitting the refuse, consisting 70 of ash, etc., to pass over into the pit or space between the girders and upon the dump plate. As in the construction illustrated, the apron may be pivotally mounted upon the upper edge of the girder and ride at its forward edge or nose upon the endless grate 75 13, or the same may be spaced and supported slightly above the surface of the grate, but sufficiently close to the same to prevent refuse from passing thereunder. The fuel may, as suggested in Fig. 1, be supplied by 80 feed hoppers 14, while above the space between the girders is located the usual bridge wall 15, preferably of masonry.

Obviously, the upper portion of the apron (it being understood that the furnace may be 85 constructed with a single grate, or may be arranged double, as illustrated in the drawing) will be protected to some extent by the accumulation of refuse, but in order to protect to the greatest possible extent that portion of the apron and the girder below the 90 line at which the angle of repose of the refuse will be tangential to the apron, the bridge wall is corbeled, so that the projection therefrom lies on or above said line; 95 and in order that the inward or exposed surfaces or walls of the apron, girder and dump plate may be kept at the minimum temperature, there is provided in the construction illustrated means whereby a forced circulation 100 of cooling agent may be induced. Preferably, this cooling agent consists of air, to the end that it may be utilized as a combustion-supporting agent on being discharged into the fuel bed, and also preferably the 105 circulation of said cooling agent is induced by steam, and specially steam produced in the boiler of the furnace in question, to the

end that the heat of said steam thus utilized may be returned to the fire bed, and thus restored to the furnace in the interest of economy. In the illustrated embodiment of 5 invention, the girder is provided with a large or major circulating chamber 16 into which the steam pressure induced air, or cooling agent is forced and from which it passes through the reduced outlets, such as 10 slots or openings 17, to a reduced or minor passage 18, located close to the inner or exposed wall of the girder, whereby the rapidity of circulation of the cooling medium in contact with said exposed wall of the girder is 15 vastly increased, with a commensurate increase in its cooling effect. From this restricted or minor passage 18 of the girder, the cooling agent passes through registering ports 19 and 20 into a correspondingly restricted passage 21, adjacent the inner or exposed wall of the apron, and around the forward edge of the diaphragm 22, forming one wall of said restricted passage 21, to the point of discharge into the fire bed. In the 25 construction illustrated, the cooling agent passes around the forward edge of the diaphragm 22 into an enlarged or major passage 23 in the apron and is discharged through ports 24, against the movable grate, 30 to assist in cooling the latter, but it will be understood that the essential object of this feature of the construction is to return the cooling agent, after it has performed its function, to the fire bed, primarily to restore 35 to the furnace the heat extracted from the furnace elements, and secondarily, to assist in supplying the furnace with a combustion-supporting agent. Both of these objects are carried out, under the most favorable circumstances, by utilizing steam as the means 40 of inducing the forced circulation of air through the passages formed in the girder and apron, for the reason that as the jet of steam enters the column of cool air, as for 45 example, in a Venturi blower, it is partly or wholly condensed and is carried with the column of air in that condition, so that when this moisture-laden air comes in contact with the heated elements of the furnace, it 50 is re-converted into steam, thereby increasing the heat-absorbing qualities of the cooling agent, and finally is discharged into the fire bed to assist in supporting combustion while restoring to a great extent, if not completely, the heat absorbed in its passage 55 through the furnace elements which have been cooled.

Similarly, the dump plate may be provided with a restricted passage or conduit 25 for conducting the cooling agent to be suitably discharged through ports 26, and the bridge wall may, as illustrated, be provided with the passage 27, for a similar purpose.

In Figs. 3 and 4 and in dotted lines in 60 Fig. 2, a conventional form of Venturi

blower is illustrated at 28, suitable pipes 29 being employed to convey the blast to the various furnace elements, heretofore described.

An important advantage of the structure 70 disclosed resides in the increased rapidity of movement of the column of cooling agent as it traverses the exposed portions of the furnace elements, as compared with its motion in traversing the protected or less exposed portions of said elements, the object in providing for this action being to increase the cooling effect thereof, by bringing a greater portion of the heat-absorbing agent 75 into contact with said exposed surfaces. Moreover, the construction and relative arrangement of the parts, with special reference to the apron, are such as to provide for replacing them, by the suitable provision of outlets from the fire-box (not shown), when 80 injured, burned out, or otherwise rendered unfit for service, without requiring the extinguishing of the fire.

It will be understood that while in Fig. 1 there is illustrated a double furnace with the 90 elements set back to back with an intermediate pit or well for receiving the refuse, two boilers being located respectively above said furnace members, the same principle of construction can be carried out in a single furnace having a wall or other masonry 95 construction closing the rear thereof, but as this is an obvious modification, it is not deemed necessary to specifically illustrate the same.

It will also be observed that in order to 100 avoid a large and heavy casting in the construction of the apron, with the consequent possibility of injury either to the apron or to the grate, by reason of the weight thereof, it is preferable to construct the apron as 105 illustrated in Fig. 4, as embodying a plurality of apron elements capable of relative independent movement in riding over the grate or obstructions on the grate, and respectively supplied with the cooling agent from the trunk afforded by the hollow girder. Moreover, these separate or independently movable apron elements are preferably 110 of sectional construction, as indicated in Fig. 4, and more particularly in detail sections, Fig. 5, wherein said sections 12^a and 12^b are secured together by means of transverse bolts 30, of which the heads and nuts are protected respectively by flanges 31 on 115 the apron sections.

It will also be noted that while means have been shown and described for introducing a moisture-laden cooling agent to the furnace elements, it is intended to 120 reserve the right to modify the same by using dry cooling agencies where the conditions necessitate or suggest the same.

What is claimed as new is:

1. A furnace comprising means for sup- 125

porting a bed of fuel, and an element having its forward edge resting upon said means and being supported at its opposite edge and having one side exposed to the heat of said fuel, said element having reverse passages therein extending toward and from said forward edge and being of unequal capacity, the smaller passage producing a high velocity of the contents for cooling purposes, and the larger passage producing a low velocity to enable the contents to be heated to aid combustion, one of said passages delivering into the other.

2. A furnace comprising means for supporting a bed of fuel, and an element having its forward edge resting upon said means and being supported at its opposite edge and having one side exposed to the heat of said fuel, said element having reverse passages therein extending toward and from said forward edge and being of unequal capacity, the smaller passage producing a high velocity of the contents for cooling purposes, and the larger passage producing a low velocity to enable the contents to be heated to aid combustion, one of said passages delivering into the other, said element also having an outlet whereby one passage can deliver the contents thereof to said fuel.

3. A furnace having a moving grate and a hollow apron at the rear of said grate, said apron having its forward edge resting upon said grate, said apron having one side exposed to the heat of the fuel upon the grate and having an internal passage of relatively restricted dimensions extending along said side toward the front of the same, and having a second passage of relatively larger dimensions extending in the opposite direction, the first passage producing a high velocity of the contents for cooling purposes, and the second passage producing a lower velocity of the contents to enable the same to be heated to aid combustion, said passages communicating adjacent the front of the apron, whereby the first passage delivers into the second.

4. A furnace having a moving grate and a hollow apron at the rear of said grate, said apron having its forward edge resting upon said grate, said apron having one side exposed to the heat of the fuel upon the grate and having an internal passage of relatively restricted dimensions extending along said side toward the front of the same, and having a second passage of relatively larger dimensions extending in the opposite direction, the first passage producing a high velocity of the contents for cooling purposes, and the second passage producing a lower velocity of the contents to enable the same to be heated to aid combustion, said passages communicating adjacent the front of the apron, whereby the first passage de-

livers into the second, said second passage having an outlet adjacent the rear of the apron, whereby the contents of said second passage can be delivered to said fuel.

5. A furnace comprising means for supporting fuel, a girder at one end thereof, means for discharging from said supporting means over and beyond the girder, said girder having an internal passage of relatively restricted dimensions extending on the exposed side and having a second passage communicating therewith, and extending in the opposite direction, said second passage being of relatively enlarged dimensions, and means for delivering a cooling agent to said second passage, the first passage producing a relatively high velocity of said cooling agent for cooling purposes.

6. A furnace having means for supporting fuel thereon, and containing a girder, said girder having reverse passages therein, extending between its lateral edges, said passages being of unequal capacity and the smaller passage being adapted to produce a relatively high velocity of the contents for cooling purposes, one of said passages delivering into the other and said other passage also having an outlet from said girder, and means for bridging the supporting means and girder.

7. A furnace having a dumping plate, members extending along the same and forming side walls therefor, said dumping plate having a chamber beneath the same with an outlet at one end and means for delivering a cooling agent to the opposite end, said members having passages extending along their exposed faces, the passages in each of said members being of unequal capacity, and the smaller passage being adapted to produce a high velocity of the contents for cooling purposes, and having outlets adjacent their upper edges and means for delivering cooling agent to said passages.

8. A furnace of the moving grate type having a loosely supported hollow apron provided with passages, and means for producing a circulation of a cooling agent therethrough, the circulation adjacent to the fire-exposed surfaces of said apron being at a greater velocity for cooling purposes, and the circulation adjacent to the less exposed surfaces, being at a smaller velocity for the purpose of heating and aiding combustion.

9. A furnace of the moving grate type having a loosely supported hollow apron provided with communicating passages, and means for producing a forced circulation of a cooling agent therethrough, the velocity of such circulation being increased adjacent to the exposed surfaces of said apron, for cooling purposes and decreased in the remainder of said passages for the purpose of heating and aiding combustion.

10. A furnace of the moving grate type

- having a hollow apron provided with communicating passages for conveying currents of cooling agents in reversed directions, an apron-supporting girder having a passage 5 in communication with a passage of said apron, and means for inducing the circulation of a cooling agent in the girder, the passage in the girder and one of the passages in the apron producing a high velocity of 10 said agent for cooling purposes, and the other passage in the apron producing a lower velocity for the purpose of heating and aiding combustion.
11. A furnace of the moving grate type 15 having a hollow apron provided with communicating passages for conveying reversed currents of a cooling agent, an apron-supporting girder having communicating passages, one of which is in communication 20 with a passage of said apron, said passage in the girder and the last named passage in the apron being for producing a high velocity of the contents for cooling purposes and the remaining passages in the apron 25 producing a lower velocity of the contents for the purpose of heating and aiding combustion, and means for inducing circulation of a cooling agent in said passages.
12. A furnace of the moving grate type 30 having a hollow apron provided with communicating passages for conveying reversed currents of a cooling agent, an apron-supporting girder having communicating passages, one of which is in communication with 35 a passage of said apron, and means for inducing circulation of a cooling agent in said passages, one of the passages of each of said elements being located parallel with the fire-exposed surfaces thereof, the said last named 40 passages being for producing a relatively high velocity of said agent for cooling purposes, and the remaining passages in the apron being for producing a lower velocity for the purpose of heating and aiding combustion.
13. A furnace of the moving grate type 45 having a hollow apron provided with communicating passages for conveying reversed currents of a cooling agent, an apron-supporting girder having communicating passages, one of which is in communication with a passage of said apron, and means for inducing circulation of a cooling agent in said 50 passages, one of the passages of each of said elements being located parallel with the fire-exposed surfaces thereof, and being of less cross sectional area than the other passage, said passages of less cross sectional area producing a high velocity of the agent for 55 cooling purposes, and the other passage for the purpose of producing a lower velocity for the purpose of heating and aiding combustion.
14. A furnace comprising a moving grate, an apron resting thereupon, a girder supporting said apron, said girder and said apron each having reversely extending passages, the passages in the apron communicating adjacent the forward end of the apron and the passages in the girder communicating adjacent the lower part of the girder, means for delivering cooling agent to one of the passages in the girder, one of the passages in the apron having an opening to discharge said agent below the grate, and the other passages in the girder and the apron being in communication with each other and being of relatively restricted dimensions, said last named passages producing a high velocity of the agent for cooling purposes, and the other passages in the apron for producing a low velocity to heat the agent to aid combustion.
15. A furnace comprising means for supporting fuel and a girder adjacent said means, said girder having reverse passages extending between its lateral edges and being of unequal capacity, the smaller passage being adapted to produce a relatively high velocity of the contents for cooling purposes, the larger of said passages delivering into the other passage and the smaller passage having an outlet from said girder, and means for bridging the girder and supporting means.
16. A furnace comprising means for supporting a bed of fuel thereon, a girder in said furnace and an apron having one side exposed to the heat of said furnace, and supported by said means and said girder, said girder and said apron having communicating passages to permit the circulation of a cooling agent, said passages producing a high velocity of the agent for cooling purposes.
17. A furnace comprising means for supporting a bed of fuel, a girder and an apron, comprising a plurality of sections, each having one side exposed to the heat of the fuel, and being supported by said means and said girder, said girder and said sections having communicating passages to permit the circulation of a cooling agent, said passages producing a high velocity of the agent for cooling purposes.

In testimony whereof I affix my signature.

JUDSON L. HAND, JR.
